CLAIM

The ornamental design for a display screen or portion thereof with animated graphical user interface, as shown and described.

DESCRIPTION

FIG. 1 is a front view of the first image in a sequence for a display screen or portion thereof with animated graphical user interface showing our new design;

FIG. 2 is a front view of the second imaged thereof;

FIG. 3 is a front view of the third imaged thereof;

FIG. 4 is a front view of the fourth imaged thereof;

FIG. 5 is a front view of the fifth imaged thereof;

FIG. 6 is a front view of the sixth imaged thereof; and,

FIG. 7 is a front view of the seventh imaged thereof.

The broken lines showing of a display screen or portion thereof forms no part of the claimed design;

The dot-dash lines in the FIGS. 1-7 represent an unclaimed boundary line and form no part of the claimed design; and,

The appearance of the transitional image sequentially transitions between the images shown in FIGS. 1-7. The process or period in which one imaged transition to another image forms no part of the claimed design.
